United States Patent Office

Des. 179,508
Patented Jan. 8, 1957

179,508

PLATE OR SIMILAR ARTICLE

A. Baker Barnhart, New York, N. Y., assignor to The Rosenthal-Block China Corporation, New York, N. Y.

Application October 21, 1955, Serial No. 38,504

Term of patent 14 years

(Cl. D44—15)

The figure is a plan view of a plate or similar article of conventional configuration, showing my new design.

I claim:

The ornamental design for a plate or similar article, as shown and described.
